SOLAR SYSTEM MODEL

Edward R. Gaul, 8555 Trouville Ave., Playa Del Rey, Calif. 90291, and Joseph L. Gaul, 912 Longwood Ave., Los Angeles, Calif. 90019

Filed Dec. 16, 1966, Ser. No. 5,068

Term of patent 14 years

(Cl. D25—1)

FIGURE 1 is a perspective view of a solar system model showing our new design;

FIGURE 2 is an elevational view thereof;

FIGURE 3 is a top view thereof;

FIGURE 4 is a side view thereof, and

FIGURE 5 is the side view opposite to the side illustrated in FIGURE 4.

We claim:

The ornamental design for a solar system model, substantially as shown.
